UNITED STATES PATENT OFFICE.

HOWARD E. HARBAUGH, OF KENOSHA, WISCONSIN.

LAMP AND LANTERN.

No. 923,970.

Specification of Letters Patent.

Patented June 8, 1909.

Application filed March 27, 1908. Serial No. 423,503.

To all whom it may concern:

Be it known that I, HOWARD E. HARBAUGH, a citizen of the United States, residing at Kenosha, in the county of Kenosha 5 and State of Wisconsin, have invented certain new and useful Improvements in Lamps and Lanterns, of which the following is a specification.

One of the objects of this invention is to 10 produce an improved means for forming a separable connection between the oil font and the remainder of the lamp, the font and the burner, or any other two sections of a lamp or lantern.

Another object is to provide means for 15 locking two separably connected lamp-sections against separation.

A further object is to simplify the construction of lamp or lantern bodies.

The invention also relates to the other improvements in lamps and lanterns herein-after set forth.

In the accompanying drawings, Figure 1 is a horizontal sectional view through a lamp 25 or lantern embodying the features of my invention, the view being taken upon the plane of dotted line 1 1 of Fig. 2. Fig. 2 is a vertical sectional view upon the plane of dotted line 2 2 of Fig. 1. Fig. 3 is a section on dotted line 3 3 of Fig. 2, illustrating the separable connection between the oil font and the burner-section. Fig. 4 is a fragmental perspective view of said burner-section. Fig. 5 is another view of the separable connection between the font and the burner section. Fig. 6 is a fragmental perspective view of one of the parts of said separable connection. Fig. 7 is a perspective detail view of one of the parts of the separable 30 connection between the font and the lamp body. Fig. 8 is a perspective view of another member of the last mentioned separable connection. Fig. 9 is a perspective view of the pivoted member for locking the lamp body and the font against separation. Fig. 40 45 50 55 60 65 70 75 80 85 90 95 100 105 110

The embodiment selected for illustration is especially adapted for use as an automobile lamp and comprises a lamp body 1, which, in practice, is secured to the automobile, and an oil font 2 separably connected with the lamp body 1. As herein illustrated the font 2 is made of drawn sheet metal and comprises two sections 3 and 4 connected together in any suitable way at 5. Near the

upper end of the font is a rabbit forming an annular shoulder 6 which may be slightly concave, as illustrated in Fig. 2. The flat upper wall 7 of the font 2 has a central opening in which is fixed a bushing 8, said bushed opening constituting, in this instance, a filling opening and also providing means for attaching the burner section 9 to the font. The burner section 9 has a central cylindrical neck 10 adapted to fit within the bushing 8. Surrounding said neck and preferably fixed to the burner section is a packing ring 11 of suitable material. The neck 10 is provided with an annular depending flange 12 to which is secured, for example, by a screw-thread connection, a ring 13 carrying a plurality of lugs 14, three such lugs being used in the present instance. Within the font and preferably attached to the lower side of the wall 7 in any suitable way, as by soldering, is a plate 15 which may be of spring material and which has an opening 16 (Fig. 6) therein to receive the lower end of the burner section. In the margin of the opening 16 is formed a plurality of notches 17, one end wall 18 of each notch being inclined as indicated in Figs. 5 and 6.

The burner section 9 is secured to the font 2 by inserting the neck 10 into the bushing 8, the lugs 14 passing through the notches 17, and then giving the burner section a partial rotation with relation to the font to carry the lugs 14 out of register with the notches 17, said lugs engaging the inclined or cam end walls 18 of said notches and placing the plate 15 under tension, thereby insuring a fluid-tight joint between the font and the burner.

The lamp body comprises a cylindrical shell or open-ended tubular waist 19 which is preferably formed of sheet metal, the lower edge of said shell being bent inward and upward to form a portion of double thickness, the lower end of said shell being adapted to rest upon the shoulder 6 of the font 2. The double thickness just referred to provides a space-ring or collar 20.

The lamp body 1 and the font 2 are separably connected by means comprising three lugs 21 secured to the font in any suitable way as by forming said lugs integral with a ring 22 and brazing or otherwise securing said ring to the lower surface of the wall 7 of said font, the lugs 21 extending upwardly

from the font and having out-turned upper ends. A plate or ring 23, preferably of spring sheet metal, is secured to the lamp body in any suitable way as, for example, by forming ears 24 upon said plate and inserting said ears into recesses 25 in the shell 19. In the plate 23 is formed a plurality of notches 26 (Figs. 1 and 7), each of said notches having a lock-strike incline 27, and said plate being provided with stop shoulders 28, said notches being adapted to receive the lugs 21.

Rotatably supported in the burner section 9 is a wick-moving shaft 29. The plate 23 has a down-turned lug 30 (Fig. 2) adapted to lie at one side of the shaft 29, and the shell 19 is grooved at 31 upon its inner face to receive the outer end of said shaft, the folded lower end of said shell being slotted 20 at 32 to permit said shaft to be inserted upward into the shell 19 when the font is to be connected with the lamp body, which latter, it will be remembered, in this particular embodiment, is assumed to be fixed in position.

Rotatably and slidably mounted in a bearing 33 in the shell 19 is a drive shaft 34 having at its outer end a finger wheel 35 and at its inner end a gear wheel 36 meshing with a gear wheel 37 on the wick-moving shaft 29. Preferably, the teeth of the gears 36 and 37 are made V-form, as shown in Fig. 10, to facilitate their interengagement when the lamp body and the font are being connected. An opening 38 is formed in the plate 23 to accommodate the gears 36 and 37.

It is desirable that the shaft 29 and the lugs 21 occupy a certain relation to each other before the font is attached to the lamp body in order that said lugs shall enter the notches 26 and the shaft shall enter the slot 32 when the operator proceeds to connect the font to the lamp body. I therefore provide means for limiting the rotation of the burner with reference to the font when these two parts are being connected. Said means may consist of a lug 39 (Fig. 6) on the plate 15 arranged to be engaged by one of the lugs 14. When the last mentioned lug stops against the lug 39, the lugs 21 and the shaft 29 are in proper position to enter the notches 26 and the groove 31 when the font is to be connected to the lamp body.

Assuming the font to be disconnected from the remainder of the lamp, the burner section 9 may be removed to permit the introduction of oil into said font, by giving said burner section a partial rotation in the direction to bring the lugs 14 into register with the notches 17. The burner section is then replaced and secured to the font by rotating the lugs 14 into engagement with the lower side of the spring plate 15 as shown in Fig. 5, one of the lugs 14 stopping against the lug 39. The font, with its burner, may now be attached to the lamp body by in-

serting said burner into the lamp body, the lugs 21 being passed through the notches 26 and the outer end of the shaft 29 being placed in the slot 32 and the groove 31. The font is now partially rotated to engage the out-turned ends of the lugs 21 with the spring plate 23, the burner section 9 meanwhile being held from movement by the engagement of the wick-moving shaft 29 with the walls of the groove 31 and the lug 30. The rotation of the lugs 21 is limited by the shoulders 28, but it will be understood that said lugs need not be rotated as far as said shoulders permit. The rotation of the lugs 21 out of register with the notches 26 is not of sufficient extent to carry the notches 17 back into register with the lugs 14, said notches being rotated into the position shown in Fig. 3. The engagement of the lugs 21 with the spring plate 23 draws the font into firm contact with the lamp body.

If desired, a positive lock may be provided for preventing separation of the oil font from the remainder of the lamp. The means herein shown for this purpose comprises a latch 40 pivoted to the plate 23 at 41, said latch carrying a lug 42 adapted to be engaged by the inner end of the drive shaft 34. A spring 43 tends to move the latch 40 into operative position to prevent the lugs 21 from being rotated into register with the notches 26 as illustrated in Fig. 1.

When it is desired to withdraw the font 2 from the lamp body, the operator pushes the drive shaft 34 inwardly to swing the latch 40 out of the path of the adjacent lug 21, and while the latch is thus held in the in-operative position, the font may be partially rotated to carry the lugs 21 into register with the notches 26 whereupon the font may be lowered away from the lamp body. When attaching the font the latch 40 may be held by the operator in its inner position, or the upper side of the adjacent lug 21 may be made sloping so as to push aside the latch 40 without the direct intervention of the operator.

It will be observed that the upper end of the oil font 2 fits within the lower end 20 of the lamp body, that said lower end is of double thickness, and that it is not weakened by being cut away or notched to receive fastening devices on the oil font.

While I have hereinbefore described my invention as applied to an automobile lamp, it is obvious that it may be applied to lamps or lanterns of various forms.

I claim as my invention:

1. A lamp or lantern consisting of a font: a lamp body having an apertured notched plate attached thereto; a plurality of lugs attached to said font and adapted to enter the notches in said plate and be rotated out of register therewith; a pivoted device carried by and within said lamp body for pre-

- venting separation of said lugs from said plate; and means for moving said pivoted device out of operative position.
2. A lamp or lantern consisting of a font; a lamp body having an apertured notched plate attached thereto; a plurality of lugs attached to said font and adapted to enter the notches in said plate and be rotated out of register therewith; a pivoted device on said lamp body for preventing separation of said lugs from said plate; and a shaft carried by said lamp body, said shaft being longitudinally movable for operating said pivoted device.
3. A lamp or lantern consisting of a font; a body; a separable rotatory connection between said font and said body; a shaft carried by said body; a wick-moving shaft carried by said font; a driving connection between said shafts; and means carried by said body for engaging said wick-moving shaft and preventing said shaft from turning with said font.
4. A lamp or lantern consisting of a font; a body; means operated by relative rotation between said font and said body for connecting them together; and a wick-moving shaft carried by said font, said body being adapted to prevent said shaft from turning with said font.
5. A lamp or lantern consisting of a font; a burner having a rotatory connection with said font; a lamp body having a rotatory connection with said font; and a wick-moving shaft carried by said burner and connected with said body to turn with said body.
6. A lamp or lantern consisting of a font; a body; a wick-moving shaft carried by said font, said body having a groove in its inner wall to receive said shaft, the latter lying wholly within said body; and means for rotating said shaft.
7. A lamp or lantern consisting of a font; a body; a separable rotatory connection between said font and said body; a burner rotatably connected with said font; a wick-moving shaft carried by said burner and lying wholly within said body; means carried by said body for engaging said shaft; and means carried by said body for rotating said shaft.
8. A lamp or lantern consisting of a font; a burner having a separable connection with said font; a wick-moving shaft carried by said burner; a lamp body; a separable connection between said lamp body and said font, said lamp body having means for engaging said shaft; and a drive shaft carried by said lamp body, and arranged to be connected with said wick-moving shaft.
9. A lamp or lantern consisting of a font; a body having an apertured notched plate attached thereto; a plurality of lugs attached to said font and adapted to enter the notches
- of said plate and be rotated out of register therewith; a burner rotatably connected with said font; a wick-moving shaft carried by said burner, said body having a groove therein to receive the outer end of said wick-moving shaft; a longitudinally movable drive shaft carried by said lamp body; a connection between said shafts; and a pivoted latch on said notched plate for preventing separation of said lugs from said plate, said latch being movable into inoperative position by said drive shaft.
10. A lamp or lantern comprising a body having an open lower end; an oil font, the upper end of which fits within the lower end of said body; and a rotary separable connection between said body and said font comprising a plate fixed in said body above its lower end, said plate having a plurality of notches therein; and a plurality of lugs fixed to and projecting above said oil font and adapted to engage said plate.
11. The combination, in a lamp or lantern, of a body and a font; means operated by relative rotation between said body and said font in one direction for connecting them together; a burner section; means operated by relative rotation between said burner section and said font in the opposite direction for connecting them together; and a connection for preventing relative rotation between said body and said burner section when the body and the font are being connected.
12. In combination, an oil font having an opening in one of its walls, a spring plate attached at its edges to said font, within the latter, said plate having an opening therein; and a burner adapted to extend through said openings and be seated upon said wall, said burner having lugs thereon adapted to engage said spring plate adjacent to the opening in said plate and place said plate under tension when said burner is rotated.
13. In combination, an oil font having a central opening in its upper wall; a spring plate attached at its edges to said font below said upper wall and having a central opening therein registering with said other opening; and a burner having a shoulder to seat on said upper wall, and a portion to extend through said openings, said portion carrying lugs adapted to enter notches in said spring plate, the latter serving to hold said shoulder tightly seated on said upper wall and being of large diameter relatively to said burner.
14. A lamp or lantern comprising a shell, the lower edge of which is bent inward and upward to form a portion of double thickness; an oil font, the upper end of which fits within said shell, said font having a shoulder thereon; and a rotary separable connection between said shell and said font comprising a spring plate fixed in said shell above its lower end, said plate having a plurality of

notches therein; and a plurality of lugs fixed to and projecting above said oil font and adapted to engage said plate, the latter serving to draw said shoulder tightly against 5 the lower end of said shell.

15. The combination, in a lamp, of an element having an annular spring plate attached thereto, said plate having notches therein, and another element adapted to 10 enter said first mentioned element, the second mentioned element having lugs upon its entering end, which lugs are adapted to engage said notched plate, the diameter of said entering end being greater than the 15 inner diameter of said annular spring plate.

16. A lamp or lantern comprising an oil font; a burner; a spring plate attached to said font; and means on said burner rotatably engaging the central portion of said 20 plate, said plate holding said burner tightly against said font during limited relative rotation of said parts in opposite directions.

17. A lamp or lantern consisting of a font; a body; means operated by relative rotation 25 between said font and said body for connecting them together; a burner; an engagement between said body and said burner for preventing relative rotation between said body and said burner; and means for rotatably 30 connecting said burner with said oil font.

18. In combination, a lamp body provided at its lower side with an open-ended tubular waist, a circumferentially extending spring supported in said waist, having a lock-strike 35 incline and made yieldable within relatively small limits axially of the waist, a font, an upstanding hooked member upon said font, adapted for rotary interlocking connection with said spring, and means limiting the 40 relative approach of the body and the font during the interlocking movements of the latter, whereby said spring is brought under tension when in locked position.

19. In combination, a lamp body provided 45 at its lower side with an open-ended tubular waist, a circumferentially extending plate-spring fixed within said waist and disposed in a plane approximately at right angles to the axis of the waist, provided with a lock- 50 strike incline and made yieldable within relatively small limits axially of the waist, a font, an upstanding hooked member upon

said font, adapted for rotary interlocking connection with said spring, and means limiting the relative approach of the lamp body 55 and the font during the interlocking movements of the latter, whereby said spring is brought under tension when in locked position.

20. In combination, a lamp body provided 60 at its lower side with an open-ended tubular waist, an annular flange-like spring having its radially outer periphery rigidly connected with the interior of the waist and its main body disposed in a plane approximately 65 at right angles to the axis of the waist, said spring being provided with a plurality of lock-strike inclines, a font, a plurality of upstanding studs upon said font each provided with a radially out-turned upper end adapted for rotary interlocking connection with said spring, and means limiting the relative approach of the lamp body and the font, whereby said spring 70 is tensioned during the movement of the 75 parts into interlocking engagement.

21. In combination, a lamp body provided 80 at its lower side with an open-ended tubular waist, a space-ring or collar of smaller diameter than the diameter of the waist fixed and arranged concentrically within the lower end of said waist, a circumferentially 85 extending flange-like plate spring supported in said waist above the space-ring and disposed in a plane approximately at right angles to the axis of the waist, said spring being provided with lock-strike inclines and notches at the entrance of said inclines, a font, and a plurality of upstanding studs rigid upon said font, each provided with an 90 out-turned upper end adapted for engagement with said flange-like spring, an annular rabbet being formed in the upper side of said font, the upstanding wall of which fits snugly within the space-ring of 95 the waist and the bottom wall of which constitutes a stop which abuts the lower end of the waist when the parts are in interlocked engagement.

HOWARD E. HARBAUGH.
